CLARENCE G. SNOOK, OF TROY, OHIO, ASSIGNOR TO THE TROY SUNSHADE COMPANY, OF TROY, OHIO, A CORPORATION OF OHIO

UMBRELLA CONSTRUCTION

Application filed April 27, 1928. Serial No. 273,265.

This invention relates to umbrellas and particularly to umbrellas of the beach and garden types.

It is among the objects of this invention to provide an umbrella which is simple but sturdy in construction, and which is adapted to withstand hard usage and abuse such as forceful impacting of the end of the umbrella against a sidewalk, to insure long life 10 of the umbrella.

Other objects and advantages of this invention will be apparent from the following description when taken in connection with the accompanying drawings and appended 15 claims.

In the drawings in which like characters of reference designate like parts throughout the several views thereof—

Fig. 1 is a central vertical sectional view 20 of the notch member and related parts in place on an umbrella rod;

Fig. 2 is a top plan view of the notch ring; Fig. 3 is a perspective view of the cover plate; and

Fig. 4 is a perspective view of the cap.

Umbrellas, particularly of the larger types such as beach and garden umbrellas, are often subjected to rigorous treatment and abuse, such as frequent and forceful impacting of 30 the end of the umbrella rod against a sidewalk or the like. These repeated jars tend to displace the notch member, which supports the fabric sustaining ribs of the umbrella, from its proper position on the umbrella rod, 35 this notch member being generally secured to the umbrella rod by several screws, tacks or the like. In actual practice, the parts on the umbrella rod frequently become loose and often are broken away entirely from their 40 supports due to this treatment, whereby frequent repairs are necessary.

The present invention provides an umbrella construction which is sturdy and which effectively withstands abuse such as that mentioned above. In the drawings, in which a preferred embodiment of the invention is illustrated, the umbrella rod is indicated at 10, the upper end of which is cut away to provide a shoulder 11 on which the notch 50 member is seated. The notch member dis-

closed herein illustrates a very satisfactory form of construction. But it is to be understood that this invention is applicable to umbrellas of this type generally to maintain any conventional type of notch member in its 55 proper position on the umbrella rod.

The notch member shown herein includes a lower notch ring illustrated particularly in Fig. 2. This comprises a metal member which is formed by cutting a blank with a series of radial tabs 14 and with the central portion of the blank stamped out and turned up to provide a series of tongues 15. A metal ring 16 is placed over the blank and the ends of the tabs 14 are bent around the ring as indicated at 17. This provides a series of apertures 18 between the tabs. The umbrella ribs 20 are bent to form hooks 21 at their upper ends and the hooks are hooked over the ring by inserting the ends of the hooks through the slots or apertures 18. The tongues 15 are then bent down, one over each hook, and serve to retain the hooks permanently on the ring so that they may swing thereon with a pivotal connection.

The notch ring is positioned over the end of the umbrella rod so that it rests on the shoulder 11. To hold this ring in place and against rotation on the rod, a cover plate 25, shown particularly in Fig. 3, is provided. 80 This plate has a central upstanding collar 26 snugly receiving the umbrella rod, and provided with apertures 27 through which attaching screws or other fastening means 28 project to fasten the same to the umbrella rod. The cover plate 25 fits down closely over the notch ring, and this plate is dented or bent downwardly as indicated at 29 to provide offsets or projections which engage between several of the bent-over tongues 15 90 to prevent the notch ring from turning around the rod.

Also positioned about the rod is a fabric-retaining member or rain-cap 30 which may be a metal stamping, having an upturned end portion 31 which snugly receives and is preferably pressed upon the rod 10. The lower portion flares outwardly as indicated at 32, and clamped between the bottom of this portion 32 and the top of the cover plate 25 100

is an umbrella fabric 34. This fabric is of course fastened to the umbrella ribs 20, but for purposes of clearer illustration this has not been shown in the drawing. Reinforcing layers 35 and 36 of fabric are preferably positioned on each side of the umbrella fabric 34.

For holding these parts in their proper position, and for preventing injury to the umbrella when the end of the umbrella rod is forcefully impacted against a hard object such as a sidewalk, a metal cap 40 is provided. This may be formed as a metal casting of sufficient thickness and strength to effectively withstand such abuse. The socket of the cap member 40 receives and engages the end 41 of the rod 10 whereby the cap is securely positioned on the end of the rod and impact does not tend to move the cap with respect to the end of the rod. This construction permits the end of the rod to be sawed off square, and eliminates the necessity of rounding off and finishing the rod end. The cap extends inwardly and contacts as indicated at 42 with the flaring portion 32 of the retaining member 30. The construction is such that the cap exerts reinforcing pressure through the retaining member 30 and layers of fabric against the cover plate 25 and notch ring of the notch member to hold these parts securely in their proper positions. The cap 40 and retaining member 30 thereby function as a single cap means for holding the notch member in its proper position. Any impacting of the end of the umbrella rod is absorbed by the cap means, and there is no tendency for the notch member to slide along the rod inasmuch as it is positively supported against longitudinal movement along the rod by the shoulder 11 on one side and the cap means on the other. In fact, any impact of the cap tends to force the notch member more tightly against the retaining shoulder 11, thereby insuring against displacement of the parts from their proper positions. The cap 40 is preferably provided with a plurality of apertures 44 which receive attaching screws 45 or the like for securing the cap to the umbrella rod. The construction not only serves to prevent the jarring of the notch member from its proper position, but also serves to protect and prevent splitting of the end of the umbrella rod, as well as to improve the appearance of the device as a whole.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In an umbrella of the character described, an umbrella rod having a shoulder,

a notch ring surrounding said rod and seating against said shoulder for supporting the umbrella ribs, a cover plate fastened to the rod for holding said notch ring in place against said shoulder and against rotation on the rod, an umbrella fabric, a retaining member positioned about said rod for clamping the fabric in place against the cover plate, and a hollow metal cap receiving and engaging the end of said rod and secured to said rod, said cap extending inwardly about said rod a substantial distance and contacting against said retaining member to thereby exert through said retaining member and fabric abutting pressure against said cover plate and notch ring, to thereby prevent impact of the end of the rod from jarring said parts from their positions on the rod.

2. In an umbrella of the character described, an umbrella rod having a shoulder, a notch ring surrounding said rod and seating against said shoulder, a cover plate fastened to said rod for holding the notch ring in place against said shoulder, said cover plate having an annular clamping surface, an umbrella fabric, a retaining member positioned about said rod having a conical portion providing a rain cap for clamping said fabric in place against the annular clamping surface of said cover plate, annular reinforcing fabric layers between said cover plate and umbrella fabric and between said retaining member and umbrella fabric, and a hollow metal cap member positioned over the end of said rod and attached to said rod, said cap member extending inwardly about said rod into contact with the conical portion of said retaining member to exert reinforcing pressure through said retaining member and fabric upon said cover plate and notch ring, to thereby prevent impact of the end of the rod from jarring said parts from their positions on the rod.

3. In an umbrella of the character described, an umbrella rod having an upper end of reduced diameter forming a shoulder, a notch member carried on said rod for supporting the umbrella ribs and seating on said shoulder, means for fastening the notch member to said rod, hollow cap means positioned over the end of reduced diameter of the umbrella rod and extending inwardly about the rod a substantial distance to exert reinforcing pressure against the notch member to prevent impact of the end of the rod from jarring the notch member from its position on the rod, and means for independently securing said cap means to said rod.

4. In an umbrella of the character described, an umbrella rod, a notch member carried on said rod for supporting the umbrella ribs, means for holding the notch member in place and against rotation on said rod, a rain cap positioned about said rod on the outer side of said notch member, and metal

cap means having a socket receiving and engaging the end of said rod and secured to said rod, said cap means extending inwardly about the rod a substantial distance to exert 5 reinforcing pressure against the rain cap and the notch member to prevent impact of the end of the rod from jarring the notch member from its position on the rod.

5. In an umbrella of the character described, an umbrella rod having a shoulder, 10 a notch ring surrounding said rod and seating against said shoulder for supporting the umbrella ribs, a cover plate attached to said rod for holding said notch ring in place 15 against said shoulder and against rotation on the rod, and cap means having a socket receiving and engaging the end of said rod and secured to said rod, said cap means extending inwardly about the rod a substantial 20 distance to exert reinforcing pressure against said cover plate and notch ring to thereby prevent impact of the end of the rod from jarring the cover plate and notch ring from their positions on the rod.

25 In testimony whereof I hereto affix my signature.
